UNITED STATES PATENT OFFICE

ERNEST E. HODSHON, OF NUTLEY, NEW JERSEY

APPARATUS FOR BANDING HATS

Application filed November 27, 1925. Serial No. 71,719.

This invention relates to hat banding and has for an object the provision of an efficient apparatus for winding an ornamental ribbon and an underlying strip of adhesive material about the crown of a hat and securing the ribbon in place by subjecting the adhesive material to the heating effect of steam.

Another object is to provide a compact self-contained apparatus of the character above mentioned which includes means for generating the steam as it is needed for each banding operation.

In the drawings:

Fig. 1 is a side elevation of the apparatus;
15 Fig. 2 is a perspective view of a hat banded
by the apparatus;

Fig. 3 is a plan view of the apparatus with parts broken away;

Fig. 4 a section on the line 4—4 of Fig. 1;
 20 Fig. 5 a section on the line 5—5 of Fig. 1;

Fig. 6 an enlarged detail section taken on the line 6—6 of Fig. 1;

25 Fig. 7 a detail side view of the structure shown in Fig. 6;

Fig. 8 a longitudinal sectional view of the

Fig. 9 a section taken on the line 9—9 of

Fig. 10 a detail perspective view of one of

Fig. 11 a section on the line 11-11 of Fig. 1.

Fig. 12 a section on the line 12-12 of Fig. 11.

Fig. 13 a longitudinal section through the steam generating unit upon a larger scale:

Fig. 14 a view of the discharge end of the steam generating unit;

Fig. 15 an enlarged view of the sealing unit, partly in section:

Fig. 16 a detail sectional view of a union in the water delivery pipe leading to the steam generating unit:

45 Figs. 17 and 18 perspective views of certain details of the structure at the discharge end of the generating unit:

Fig. 19 a side elevation of a portion of the apparatus showing a hat mounted on the block and the steaming and roll supporting members rocked away from the block:

Fig. 20 a view illustrating the beginning of the banding operation;

Fig. 21 an enlarged detail section taken on the line 15—15 of Fig. 1 showing the counting mechanism;

Fig. 22 a detail view of the water and compressed air tank; and

Fig. 23 a detail view showing the final step in the hat banding operation.

Referring to the various parts by numerals, the apparatus includes a table 1 supported on legs 2. Supported over the center of the table is an expandible hat block B, so mounted that it may be rotated about a horizontal axis and also moved through a circular orbit of small diameter. A steam generating and discharge unit S is supported adjacent to the block B and is directed toward it. The block is mounted for said compound movement in order to maintain it in proper relation to the unit S during a hat steaming operation which will be described later. 60 65 70

The means for supporting the block includes a pedestal 3 mounted upon and bolted to the table. At the upper end of the pedestal 3 is formed a bearing 4 in which is journalled a short horizontally disposed shaft 5 of relatively large diameter and formed with a longitudinal bore 6. This bore is eccentrically located in the shaft and has journalled in it a slender shaft 7. The shaft 7 emerges through the opposite ends of the shaft 5 and has an internal gear 8 fixed to one of its emerging ends. To the opposite end of the shaft 7 is fixed a plate 9 which supports the hat block. An upwardly extending bracket 10 is secured to the pedestal 3 and supports a short stub shaft 11 at its upper end in alinement with the center of the large shaft 5. This shaft 11 is secured to the bracket by a set screw 12 and projects into the eccentrically located internal gear 8. A pinion 13 is fixed to the stub shaft and meshes with the internal gear. The diameter of the pinion is one half that of the gear. When the large shaft 5 is turned the eccentric shaft 7 and the internal gear 8 will be moved through a circular orbit and the fixed pinion 13 will cause said gear and shaft to rotate a half revolution for each full revolution of 10

the large shaft. In order to turn the large shaft a hand wheel 14 is fixed to one end of said shaft adjacent the internal gear 8. The hat block B is elliptical in form and by moving it as described its peripheral surface will be maintained in a substantially uniform spaced relation to the heating unit S throughout a complete rotation of the block.

The elliptical block B is divided along its major and minor axes into four sections 15 adapted to be expanded apart to vary the circumference of the block and adapt it to fit hats of different sizes. Each block section 15 is secured to a supporting bar 16. These bars 16 are carried by the plate 9 and are slidably mounted in radially extending retaining grooves 17 formed in said plate. A plate 18 is rotatably mounted upon the small shaft 7 and bears against the inner face of the plate 9. The plate 18 is formed with four eccentric cam slots 19. Projecting from each supporting bar 16 is a pin 20 which extends through one of four clearance openings formed in the plate 9 and into one of the cam slots 19 formed in the inner plate 18. A rotation of the plate 18 in one direction upon the shaft 7 will cause the cam slots 19 to move the bars 16 and the block sections 15 radially outward to expand the hat block. When said plate is rotated in the opposite direction the block sections will be contracted together by the cam slots. In order to turn the plate 18 an operating ring 21 is provided. This ring encircles the bearing 4 and is rigidly connected to the plate 18 in spaced relation thereto by spacing arms 21'. A plate 22 is secured over the exposed face of the plate 18 to cover the cam slots.

It is desirable that the gaps, formed in the peripheral surface of the hat block by the expansion thereof, should be bridged, in order to provide a firm, continuous surface for certain pressing operations performed in connection with the banding of the hat. A plurality of bridge members 23 are provided. Said members are formed of sheet metal and are substantially L-shaped, each member including a bridge portion 24 and an angularly extending guide portion 25. The bridge portion 24 is slightly arcuate in cross section and is adapted to extend across the gap between two of the block sections and to bear upon the peripheral surface of the block at opposite sides of the gap. The guide portion 25 is disposed between the block sections and the plate 9 and is mounted to slide radially of the plate. A headed screw 26 extends through an elongated slot 27 in the guide portion 25 and into the plate 9 to retain the bridge member upon said plate. The bridge members are yieldingly drawn inward toward the center of the block by radially disposed tension springs 28 connected to the guide portions 25 of the bridge members and to the plate 9. These springs hold the bridge

portions 24 firmly against the peripheral surface of the block in all of its expanded and contracted positions. Each block section has an abutment member 29 secured to it at its rear face and extending outwardly beyond the peripheral surface of the block. These members serve as stops for the brim of a hat placed upon the block.

The steam generating and discharge unit S is supported adjacent the hat block by a rockable standard 30. This unit includes a cylindrical shell 31. Secured across one end of said shell is a plate 32 formed at its inner face with an annular flange 33 adapted to fit over the end of the shell. Screws 34 secure the flange 33 to the shell. The plate 32 is also formed with a flange 35 extending from its outer face. This flange 35 is square in outline. A helically coiled water pipe or tube 36 of small diameter is arranged longitudinally within the shell 31 and has one of its ends 37 emerging through the side of the shell, and its opposite end 38 extending outwardly through an opening 39 formed in the plate 32 and into the enclosure formed by the flange 35. The end 38 of the pipe is directed inwardly toward the outer surface 40 of the plate 32 and is formed with a discharge opening 41 in close proximity to said surface.

A heating unit H extends into the shell 31 and includes a porcelain plug member 42 and a porcelain socket member 43. The plug member 42 is substantially in the form of a hollow cylinder formed with a helical groove around its outer surface. Wound in said groove is a coiled resistance wire 44. One end of the socket 43 fits within the shell 31 and into said end the plug member is threaded as at 45. The ends of the resistance coils lead to contacts within the socket member. These contacts are adapted to make electrical connection in the usual way with circuit wires 46 leading into the socket member. The plug member 42 extends centrally throughout the length of the shell 31 and bottoms against the plate 32. Secured to the inner side of the plate 32 is a small tapered porcelain plug 47 which is adapted to enter the end of the plug member 42 and center it within the shell. The entire heating unit H is held to the shell 31 by a retaining cap 48 which encloses the socket member 43 and is threaded upon the end of the shell. Interposed between the outer end of the socket member and the cap is a spring washer 49 which yieldingly holds the unit H pressed inwardly against the plate 32 and allows the various parts to expand slightly when heated.

Stretched across the enclosure formed by the flange 35 is a sheet of wire gauze 50. This sheet is folded back over the outer straight sides of the flange and is held in place by a split clamping member 51 which surrounds the flange 35 and is adapted to be clamped against the gauze by a bolt 52 which

is passed through outwardly turned ears 53 formed at the split in the clamp. Mounted to slide across the gauze-covered aperture defined by the flange 35 is a trough-like shield 54. The upturned sides 55 of the shield are adapted to slide over the sides of the clamping member, and the shield is retained upon said member by screws 56 which pass through elongated slots 57 in the upturned sides 55 thereof and into the clamping member. The slots 57 permit the shield to be moved across the aperture to vary its width.

Secured to one end of the table as at 58 is a tank or reservoir 59. This tank is adapted to contain water and compressed air. The water is charged into the tank through an opening at the top which is closed by a threaded plug 60. This plug carries a valve through which air may be forced into the tank by any suitable means. A gauge 61 mounted upon the top of the tank is adapted to register the degree of air pressure therein. A small tubular conduit 62 leads from the tank to a manually operable valve 63 mounted on the upper face of the table. From the valve 63 a similar conduit 64 leads upwardly over a standard 65, rigidly mounted upon the table, and thence downwardly to the emerging end 37 of the tube 36 to which it is joined by a union 66. Interposed between the joined ends of said tubes, within the union, is a washer 67 formed with a restricted opening 68 through it.

Rigidly mounted upon the table at the opposite side of the hat block from the standard 30 which supports the unit S, is a standard 69. The upper end of this standard 69 has secured to it an arcuate segment 70 formed with ratchet teeth. A support 71 for rolled strips of hat ribbon and rubber cement is pivotally mounted as at 72 upon the base 73 of the standard 69 and extends upwardly alongside said standard. The support 71 is in the form of a flat plate and its upper end is in the shape of a handle 74. Mounted upon the handle is a spring pressed latch device L which is adapted to engage the toothed segment 70 and hold the support in different adjusted positions. A pair of spaced spindles 75 and 76 are rigidly carried by the upper end of the supporting plate 71 and project outward horizontally from the plate in directions parallel to the direction of the axis of the hat block. The spindle 75 is adapted to rotatably support a spool 77 of ribbon and the spindle 76 is adapted to rotatably support a spool 78 of rubber cement in strip form. In order to prevent said spools from turning too freely upon the spindles a presser disk 79 is mounted upon each spindle over the outer face of the spool. These disks are yieldingly pressed inwardly against the spools, to hold them against the plate 71, by springs 80 encircling the spindles and interposed between the presser disks and collars 81 mounted upon

the spindles. These collars are adapted to be shifted along the spindles to different positions to vary the tension of the springs 80 and are adapted to be held in their adjusted positions by set screws 82.

The ribbon R and the strip of cement C are adapted to be trained toward the hat block in superposed relation between a pair of horizontally disposed tension rollers 82' and 83 mounted one above the other in a U-shaped yoke 84 secured to the supporting plate 71. The upper roller 82' is rotatably mounted upon a shaft 85 which is hinged at one end to the yoke as at 86. The opposite end of the shaft is yieldingly retained within a notch at the opposite side of the yoke by a snap spring 87. The shaft and roller are thus adapted to be swung upwardly away from the lower roller to facilitate the training of the ribbon and the cement strips between the rollers. The lower roller 83 is pressed upwardly toward the upper roller by a bowed leaf spring 87', the tension of which is adjusted by a screw 88 threaded through the yoke 84. This lower roller is mounted upon a shaft 89 the ends of which extend through vertically elongated slots in the opposite sides of the yoke.

The standard 30 which supports the unit S is pivotally connected at 90 to a base bracket 91 rigidly mounted upon a block 92 secured to the table. The standard is formed with an arm 93 extending below the pivot 90. This arm has a pin and slot connection with a bar 94 mounted to slide horizontally within the base bracket 91. This bar is formed within the bracket with ratchet teeth 95 and extends outwardly from the bracket in the direction of the hat block. A reach rod 96 is pivotally connected at one end to the outer end of the bar 94, extends along the table, and is pivotally connected at 97 to the spool supporting plate 71 above the pivoted connection 72 thereof. The plate 71 and the standard 30 are thus connected together by the reach rod 96 and the bar 94 to be moved in unison toward or from the hat block when the said plate 71 is rocked by the handle 74.

Mounted upon the base bracket 91 is a small counting mechanism 98. This mechanism has a rockable operating arm 99 which extends downwardly within the bracket and into engagement with the teeth 95 on the bar 94. As the bar 94 is moved by the rocking movement of the standard 30 and the spool supporting plate 71, as just described, the counting mechanism will be caused to register the number of said movements. The bracket is formed to cover and conceal the actuating arm 99 and the ratchet teeth 95 in order to prevent tampering with or accidental operation of the counting mechanism.

The upper end of the rigid standard 65 carries a laterally extending arm 100. Suspended from this arm by means of a spring

101 is an electrically heated sealing unit 102. This unit includes a handle 103 and a T-shaped heating iron 104 connected to the handle by a shank 105 and a sleeve 106. Within said sleeve is a resistance coil 107 for heating the iron. The sealing unit is normally suspended by the handle, above the hat block and slightly back of it in order to be out of the way of the hat brim when a hat is placed upon or removed from the block.

The arm 100 is connected to the upper end of the standard 65 by means of a four-way union 108. Leading into the top of said union are the main conducting wires 109 connected at their outer ends to a plug 110 by which they may be connected to the line wires. A socket member 111 provided with a switch is carried by the union 108 and this socket in turn carries a multiple socket member 112. Both of these socket members are electrically connected to the wires 109. The wires 46 are plugged into the socket member 112 and lead therefrom to the socket member 43 of the steam generating unit S. This connection supplies current to the resistance coil 44 of said unit. Wires 113 plugged into the socket member lead to the resistance coil 107 of the sealing unit 102 and supply it with current. A lamp 114 plugged into the socket member 112 indicates when the current is turned on.

The apparatus is operated as follows: A hat is placed upon the block with its brim abutting the stop members 29. The block is expanded to fit the hat by turning the ring 21. The block sections are locked in an expanded position by a latch 115 carried by the rotatable plate 18 and pressed by a spring 116 into notches 117 formed in the plate 9. This latch is manually releasable by the operation of a projecting finger 118. This adjustment of the block is, of course, necessary only when operating upon hats of different sizes. When the block is once adjusted for a given size it needs no further adjustments to receive successive hats of that size. The ribbon R and the cement strip C are drawn through the tension rollers 82 and 83 to the hat in superposed relation, with the ribbon uppermost. The free ends of the ribbon and strip are placed by the operative in proper position upon the hat crown. The sealing unit 102 is manually pulled down against the resistance of the spring 101 and its heated iron 104 pressed against the end of the ribbon. The heat and pressure from said iron will render the underlying layer of rubber cement adhesive and cause the end of the ribbon to be quickly sealed to the hat. When the sealing member is released the spring 101 automatically elevates it away from the hat. The block is then turned by the hand-wheel 14 to wind the ribbon and cement strip about the hat

crown. The tension rollers and the spring-pressed presser disks 79 keep the ribbon taut and in proper position upon the crown as it is wound. When the ribbon and strip have been extended around the crown they are severed and the severed ends of the wound portion are sealed to the crown by the sealing iron.

The valve 63 connecting the water conduits 62 and 64 is next manually opened. Water is then forced by the compressed air in the tank 59 through said conduits to the union 66 which connects the conduit 64 and the pipe 37. The flow of water is here properly restricted by the small apertured washer 67. The water then flows through the pipe 37 and the coiled pipe 36 of the steam generating unit. As the water passes through the coiled pipe it is converted into steam by the heat from the resistance coil 44. The restriction washer 67 determines the maximum flow of water to the generator in accordance with the capacity of the latter to convert the water into steam. The restriction thus prevents flooding of the generator and ensures the generation of dry steam.

The steam is discharged through the nozzle end 38 of the coiled pipe, against the outer surface 40 of the plate 32. This plate is heated by the resistance coil and its heated surface 40 reheats the steam discharged against it and scatters or diffuses it. This steam is directed by the flange 35 through the gauze 50 and against the ribbon wound upon the hat crown. The scattering of the steam by the surface 40 causes it to emerge evenly through the entire surface of the gauze instead of passing out in the form of a concentrated jet. The hat block is rotated a full revolution to bring the entire length of the ribbon successively in the path of this steam jet. The heat from the steam penetrates quickly through the ribbon to the underlying cement strip and renders it adhesive. The steam is thus generated in the generating unit as it is needed for each operation. When the steaming operation is completed, the valve 63 is operated to shut off the flow of water to the steam generator, and the unit S and the ribbon roll support are expanded away from the hat block by releasing the latch L and moving the handle 74 to the right as viewed in Figs. 1 and 19. A pair of rollers 119 carried by a handle 120 are pressed against the ribbon, directly the said unit and ribbon roll support have been moved out of the way, and the hat block is again rotated. This pressure irons out the ribbon and causes the cement to intimately unite it with the hat. The entire banding operation is then completed and the hat is removed from the block.

The steam generating and discharge unit S is removably supported in any suitable manner upon an arm 121 carried by the upper end of the standard 30. This arm, when the standard 30 is swung inwardly, supports the

unit directly radially toward the center of the hat block with its discharge end in close proximity to the hat upon the block. In this position, the discharge end of the unit bears against the hat brim, and in order to protect the brim from the heat, one side of the split clamping member 51 is covered with a facing 122 of asbestos which contacts the brim. Before each steaming operation the shield 54 is adjusted across the steam discharge aperture to properly fix the width of said aperture with relation to the width of the ribbon to be steamed. The number of the steaming operations is recorded by the counting mechanism 98 which is automatically operated each time the steaming unit S is swung into operative position. The desired spaced relation between said unit and the hat is obtained by the proper adjustment of the handle 74 and latch device L along the segment 70.

It will be seen from the foregoing that I have provided a highly efficient and compact apparatus. The means for winding the ribbon, for steaming it, and for generating the steam are all combined to form a portable self contained unit.

What I claim is:

1. In an apparatus of the class set forth, a rotatably mounted hat block formed of sections mounted and arranged to be expanded apart and contracted together to vary the circumference of the block; a plurality of rigid bridge members mounted upon the block to shift radially thereof and formed and arranged to bridge the gaps formed in the peripheral surface of the block when its sections are expanded apart; resilient means adapted to yieldingly hold said bridge members in contact with the peripheral surface of the block in all of the expanded and contracted positions of the block sections; an electrically heated sealing member; and means shiftably supporting the sealing member above the hat block and adapting it to be moved into contact with a hat upon the block, the bridge members being adapted to resist the pressure of the sealing iron and firmly support the hat at the gaps between the block sections.

2. An apparatus of the class set forth comprising a hat support, steam discharge means, a support for the said discharge means adapted to be shifted to move said means to and from a position to discharge steam upon a hat mounted upon said hat support, a support for rolled strips of ribbon and rubber cement located adjacent the hat support and adapted to be shifted to move said rolled strips toward and from the hat support, and means connecting the support for the rolled strips with the support for the discharge means to adapt said supports to be shifted in unison.

3. An apparatus for banding hats comprising a table or main support; a hat support rotatably mounted thereon; an electrically heated steam generating and discharge

unit; means shiftably supporting said unit upon the main support to move toward and from the hat support; a support for spools of ribbon and rubber cement in strip form mounted upon the main support adjacent the hat support; a water tank adapted to hold air under pressure; a supply pipe leading from said tank to the said generator; a manually operable valve in said pipe to control the flow of water to the generator; and means adjacent the generator to restrict the flow of water from the said pipe into the generator when the said valve is open and determine the maximum flow of water in accordance with the capacity of the generator to convert the total amount of water supplied to it into steam.

4. In an apparatus for banding hats, a rotatably mounted hat support; an electrically heated steam generating and discharge unit to discharge steam upon a hat on said support; a water tank adapted to hold air under pressure; a supply pipe leading from said tank to the generator; and a manually operable valve in said pipe to control the flow of water to the generator, the generator being constantly open to discharge the steam as it is generated and prevent an accumulation of pressure in the generator.

5. In an apparatus of the class set forth, a rotatably mounted hat block formed of segmental sections mounted and arranged to be radially expanded apart and contracted together to vary the circumference of the block; manually operable means to expand or contract said block sections; a plurality of rigid, segmental bridge members formed separately from the block sections, formed and arranged to bridge the gaps in the peripheral surface of the block when its sections are expanded apart and to bear against the peripheral surfaces of the sections at opposite sides of the gaps; guiding and retaining extensions carried by said bridge members and extending inwardly from the block periphery; means guiding said extensions for radial movement relatively to the block along lines intermediate the radial lines of shift of the block sections; and springs yieldably and constantly holding said bridge members against the block periphery to permit them to expand with the block and cause them to contract therewith to keep the gaps closed and automatically maintain the continuity of the peripheral surface of the block.

In testimony whereof I hereunto affix my signature.

ERNEST E. HODSHON.
